UNITED STATES PATENT OFFICE.

HIRAM H. GIBBS, OF INDIANAPOLIS, INDIANA.

ROAD-CART.

SPECIFICATION forming part of Letters Patent No. 408,969, dated August 13, 1889.

Application filed January 18, 1889. Serial No. 296,781. (No model.)

To all whom it may concern:

Be it known that I, HIRAM H. GIBBS, of Indianapolis, county of Marion, and State of Indiana, have invented certain new and useful 5 Improvements in Adjustable and Flexible Foot-Rests for Road-Carts; and I do hereby declare that the following is a full, clear, and exact description thereof, reference being had to the accompanying drawings, in which like 10 letters refer to like parts.

My invention relates to the construction of foot-rests for road-carts; and it consists in making the foot-rest flexible and adjustable, so that it can be easily drawn up out of the 15 way of the driver when he desires to convert the road-cart into a trotting-sulky, as will be understood from the following description.

In the drawings, Figure 1 is a side view of my device in place, the dotted lines indicating the position of the straps when the rest is brought up beneath the seat out of the way. Fig. 2 is a detail view of one of the fastenings for locking the side straps when drawn up. Fig. 3 is a front view of the eye of the same. 25 Fig. 4 is a rear view of a road-cart or sulky, showing the foot-rest suspended by the straps. Fig. 5 is a detail view of the buckle which serves as a fastening for the central strap. Fig. 6 is a side view of Fig. 5. Fig. 7 is a 30 front view of the roller for the side straps. Fig. 8 is an end view of the same. Fig. 9 is an edge view of one form of my hook formed integral with the ear. Fig. 10 is a rear end view of the same. Fig. 11 is a front view of 35 the central ear with the tongue formed integral therewith. Fig. 12 is a side view of the same. Figs. 1 and 4 are drawn on a smaller scale than the other figures.

In detail, *f* is a foot-rest, its sides composed 40 of straps *1*, which are fastened to the front end around rollers *r*, mounted in a clip connected to the cross-bar *c*. The rear end of these straps pass through eyes *e*, fastened beneath the seat, these preferably having projections or hooks *h*, over which the ends of 45 the strap pass.

2 is a central strap, its forward end connected to the rear slat of the foot-rest, its upper end passing through the guide *e'*, fastened beneath the seat *s'* centrally, and having

a tongue *t*, which hooks through the holes in the strap. The slats *s'* are riveted to the straps, as shown in Fig. 4.

3 is an additional strap, its forward end fastened beneath one of the central slats of the 55 foot-rest, its front end fastened about the axle *a* of the cart. It will be seen, therefore, that the foot-rest is composed of slats fastened to the central and side straps, thus making the whole flexible, and the rear ends of these 60 straps are all fastened through eyes or guides directly beneath the driver's seat and their ends are within easy reach of his hand.

If, now, while the device is in the position shown in the full lines in Fig. 1 the driver desires to speed his horse, he takes hold of the central strap *2* and pulling upon it he can draw the foot-rest up in the position shown in the dotted lines in Fig. 1, and the end of this strap will pass down through the central 65 guide *e'* and may be hooked at the desired point over the tongue *t*, or he may make the same adjustment by drawing up the side straps *1* and fastening them on the hooks *h* in a similar manner. While this adjustment 70 is going on the driver's feet can rest upon the cross-bar of the shaft or stirrups, and when completed the foot-rest will be completely out of the way of his own feet, as well as out of the way of the horse's hind feet, for the horse 75 when trotting rapidly reaches backward with its hind feet a much greater distance than when going at a less speed, and an ordinary road-cart having a rigid foot-rest is not adapted to speeding horses, as this foot-rest hangs 80 down directly in the way of the horse's feet when traveling fast.

My device practically makes the ordinary road-cart convertible into a racing-sulky by making the foot-rest flexible and adjustable 85 in the manner herein described.

In Figs. 2 and 3 the hook and eye are shown in separate pieces attached by screws to the under side of the bar; but I preferably make them in the manner shown in Figs. 9, 10, 11, and 95 12, in which the eye and hook are formed integral with the common shank, and the strap being slipped through the eye is hooked over the projection or tangent *h*, securing it in place, and the device thus constructed can be 100

attached by a single screw to the under side of the bar, and the eye which serves as a guide for the strap and the projection forming the hook or tongue are always in line and the strap is easily fastened or loosened from engagement with the hook, and when fastened or loosened will be held perfectly tight.

What I claim as my invention, and desire to secure by Letters Patent, is the following,

to wit:

1. A foldable foot-rest for road-carts, its sides composed of flexible bands or straps, slats secured across and fastened to the same, the forward end of these straps secured near or to the cross-bar, the rear end adjustably fastened beneath the driver's seat, with means for securing the same at any desired height, substantially as shown and described.

2. An adjustable and flexible foot-rest for road-carts, comprising the side straps 1 1, central strap 2, connected by cross-slats, the front ends of the side straps connected to the cross-bar, and the forward end of the central

strap connected to the foot-rest, the rear ends of all these straps connected beneath the seat 25 within easy reach of the driver's hands, with means for adjusting and securing such straps at any desired height, substantially as shown and described.

3. In combination with a road-cart, the flexible and foldable foot-rest for the driver, composed of two or more flexible straps, their forward ends adjustably connected at or near the shaft cross-bar, their opposite ends connected at the sides or beneath the driver's 35 seat, a series of slats riveted to such strap and forming a rest for the feet, the whole adapted to be drawn up beneath the seat, out of the way of the driver's feet, substantially as shown and described.

In witness whereof I have hereunto set my hand this 14th day of January, 1889.

HIRAM H. GIBBS.
